HYDRAULIC TORQUE RELIEF MECHANISM
Mortimer J. Huber, St. Paul, Minn., assignor to Motion
Products Manufacturing Company, Inc., Ramsey Coun-
ty, Minn., a corporation of Minnesota
Filed May 11, 1965, Ser. No. 454,780
8 Claims. (Cl. 40—33)

This invention relates to an improvement in hydraulic torque relief mechanism and deals particularly with a drive unit designed particularly for the use in driving rotary elements which are subjected to varying pressures.

Rotary signs for advertising purposes are now commonly used. Many of these signs are supported for rotation about a vertical axis. Some of the signs may be viewed from various directions. For example, Filling Stations which are located at the intersection of highways, often use signs of this type which rotate relatively slowly but with sufficient speed so that they can be viewed easily from any direction during some part of their rotation. While not specifically limited to signs of this type, the present hydraulic torque relief mechanism is designed to connect a motor such as an electric motor which rotates at a constant speed with a vertical shaft on which the rotary sign is mounted.

One of the difficulties which is often experienced with signs of the type in question lies in the fact that the signs, being of considerable width and height, are subjected to severe pressures when acted upon by winds of high velocity. While the motors which drive such signs are usually connected to the signs through a gear reduction unit which acts to rotate the sign at a small fraction of the speed of rotation of the motor, there is often sufficient force against the sign during some part of the rotation to place a severe strain upon the drive motor. As the sign rotates from a "feathered" position to a position broadside of the wind, there is a considerable leverage tending to stop the rotation of the sign until the time when it is at right angles to the direction of the wind. After passing this position, there is also a considerable force multiplied by the leverage acting to continue the rotation of the sign until it is again aligned with the direction of the wind. These forces are extremely detrimental to the drive motor if the sign is directly connected. While the difficulty may be somewhat alleviated by the use of slip clutches and the like, clutches of this type must be replaced at short intervals due to wear, and often cause very erratic movements of the sign itself.

Due to the fact that signs of the type in question usually work for many hours each day, and in some instances work continuously, the gear reduction units which connect the drive motor to the sign usually comprise hollow housings containing the gears which are substantially filled with lubricating oil to prevent excessive wear. I have found that if a simple hydraulic clutch is provided between the drive motor and the drive shaft of the sign which is normally submerged in the lubricating fluid, much of the previous difficulties may be obviated. The type of hydraulic clutch in question, may comprise a rotor having projecting vanes and which rotates within a stator having inwardly projecting vanes which terminate in close proximity to the rotor vanes. The casing which encloses the rotor is apertured so that the housing is at all times submerged in fluid. As a result, the rotation of the rotor by the drive motor may exert a tremendous hydraulic force against the stator, tending to rotate the stator in unison with the rotor. At the same time, there is no positive drive between the rotor and stator, and as a result, if sufficient leverage is exerted upon the sign, the speed of rotation of the stator may be very materially reduced. As a matter of fact, if the sign is subjected to sufficient wind pressure during its rotation, the stator may

2

actually rotate in a reverse direction relative to the rotor without stressing the drive motor beyond its normal capacity.

A feature of the present invention resides in the provision of a construction of the type described in which the rotor is driven at the same speed as the drive motor, and in which the vanes of the rotor are sufficiently close to the vanes of the stator so that the stator is normally rotated at a speed almost equal to the speed of rotation of the rotor. At the same time, there is sufficient clearance between the vanes of the two units so that slippage can occur under conditions of high stress.

A further feature of the present invention resides in the provision of a unit of the type described in which the rotor is provided with a series of angularly spaced vanes, the stator is provided with what is usually a similar number of inwardly projecting vanes, in which the housing of the stator fits snugly about the rotor. Angularly spaced apertures are provided in the housing, but these apertures are angularly spaced a distance which is greater than the spacing between the vanes in both the rotor and stator. As a result, there is a space between the apertures where the fluid driven by the rotor acts directly against the vanes of the stator tending to rotate the two parts in unison.

These and other objects and novel features of the present invention will be more clearly and fully set forth in the following specification and claims:

FIGURE 1 is a plan view of the lower portion of the gear housing with the upper portion thereof removed, certain of the parallel shaft being shown in section.

FIGURE 2 is a vertical section through the gear housing, the position of the section being indicated by the line 2—2 of FIGURE 1.

FIGURE 3 is a vertical sectional view through the gear housing, the section being at right angles to the section shown in FIGURE 1, and the position of the section being indicated by the line 3—3 of FIGURE 1.

FIGURE 4 is an enlarged vertical section through the hydraulic clutch unit forming a part of the drive mechanism, the position of the section being indicated by the lines 4—4 in FIG. 5.

FIGURE 5 is a top-plan view of the clutch unit illustrated in FIGURE 4.

FIGURE 6 is a horizontal sectional view through a hydraulic clutch unit, the position of the section being indicated by the line 6—6 of FIGURE 4.

FIGURE 7 is a diagrammatic elevational view of a sign, showing the drive mechanism connected thereto.

With reference first to FIGURE 7 of the drawings, the drive unit 8 is illustrated in general by the letter A, while the rotatably driven sign is indicated in general by the letter B. The sign B rotates about the vertical axis 10. A supporting plate 11 is indicated on a horizontal plane beneath the sign, the mounting plate 11 being supported by a suitable framework which is not illustrated in the drawings. A bearing 12 is mounted upon the mounting plate 11 and supports a vertically extending shaft which is arranged on the axis 10. The lower end of the shaft 13 is connected to a driven shaft 14 which projects from the drive unit A. A motor 15 is supported by the drive unit and acts through suitable means in the gear housing A to drive the driven shaft 13 and therefore to rotate the sign B about its vertical axis.

As is indicated in FIGURES 2 and 3 of the drawings, the drive unit A includes an upper section 16 and a lower section 17. The upper section 16 includes a generally flat top panel or plate 19 and downwardly depending peripheral side walls 20. The lower section 17 includes a bottom plate or panel 21 to which is secured upwardly extending peripheral side walls 22. The side walls 20 and 22 of the two sections normally meet in edge

abutting relation, and a gasket 23 extends therebetween to seal the two units together. The two sections are connected together by suitable means such as cap screws 24 extending through apertures in the peripheral walls of the upper section and threaded into internally threaded apertures in the lower section.

The drive motor 15 is secured to the bottom plate 21 of the lower section 17 and includes a motor shaft 25 which extends through the bottom panel 21 of the gear housing, and through a suitable bearing 26 and seal 27. The clutch unit which is indicated in general by the letter C is mounted upon the motor shaft 25 and acts through the hydraulic clutch C to rotate a concentric pinion 29. As is indicated in FIGURE 1 of the drawings, the pinion 29 is in mesh with a gear 30 mounted upon a vertical shaft 31 which is shown as supported by suitable bearings 32 and 33 in the top and bottom housing portions 16 and 17. A pinion 34 is mounted upon the shaft 31 and is in mesh with a gear 35 on a parallel vertical shaft 36 supported vertically in the housing by means of bearings 37 and 39 best illustrated in FIGURE 3 of the drawings. A pinion 40 on the vertical shaft 36 is in mesh with a gear 41 mounted on the drive 14. Thus, it will be seen that rotation of the motor shaft 25 of the motor 15 acts through the gear train within the housing of the drive unit A to drive the driven shaft 14 at a greatly reduced speed. As will be understood, the driven shaft 14 is coupled to the vertical shaft 13 which drives the rotary sign B.

Due to the severe strain which is placed upon the shaft 14, this shaft is supported by a pair of spaced bearings 41' and 42 mounted in bearing cups 43 and 44 formed as a part of the upper and lower sections 16 and 17 of the housing. Seals 45 and 46 are provided to protect the housing from leakage.

The hydraulic clutch unit is best illustrated in FIGURES 4, 5, and 6 of the drawings. This unit C includes a rotor 49 which is pinned or otherwise secured to the motor shaft 25 by means of a pin extending diametrically through the rotor 49 and shaft 25 through the diametrically extending aperture 51. As is indicated in FIGURE 6 of the drawings, the rotor 49 is provided with a considerable number of angularly spaced vanes 53 which are preferably evenly spaced. Rotation of the motor shaft 25 thus causes rotation of the rotor 49.

The stator of the clutch unit C is indicated in general by the numeral 54. The stator includes a bottom plate 55 from which depends a hub 56 which is lined by a suitable bearing 57. The bottom plate 55 fits snugly beneath the rotor 49. The stator also includes a top closure plate 59 which adjoins the upstanding peripheral walls 60 on the bottom plate 55 by a rabbeted joint 61 to prevent leakage. A closure plate 59 is secured to the lower portion of the stator housing by means of cap screws 62 or by other suitable means.

The cover plate 59 is provided with an upwardly projecting hub 63 which accommodates a vertical shaft 64 which supports, or forms, the pinion 29. The shaft 64 is secured for rotation with the hub 63 by means of the pin 65 or other suitable means. The lower end of the hub 63 is grooved as indicated at 66 to accommodate a bearing 67 encircling the reduced diameter portion 69 of the motor shaft 25 to hold the shaft 64 and motor shaft 25 in alignment.

A cylindrical flange 70 extends upwardly from the top closure plate 59, and a series of angularly spaced apertures 71 extend through the top closure plate above the vanes of the rotor 49. Similar angularly spaced apertures 72 are provided through the bottom plate 55 inwardly of the cylindrical flange 73.

Due to the fact that the clutch unit C is constantly submerged in lubricating oil, rotation of the rotor 49 tends to cause the rotation of the stator unit 54 in unison therewith. The apertures 72 and 71 are angularly spaced a distance in excess of the angular distance between the

radially extending vanes 53 of the rotor 49 which increases the tendency for the stator to rotate in unison with the rotor. However, if there is sufficient wind acting upon the sign B, the rotary movement of the sign may be slowed down, halted, or the sign may actually reverse in direction until the wind pressure abates and permits the continued rotation of the sign.

There is a similar force which tends to retard the rotation of the sign when the wind forces thereupon tend to rotate it faster than is permitted by the motor. As a result, if sufficient wind is exerted against the sign, it may rotate the sign toward feathered position during gusts of wind of high velocity. When the gusts of wind abate, the sign can then continue its normal rotation.

In accordance with the patent statutes, the principles of construction and operation of this improved hydraulic torque relief mechanism have been described, and while an endeavor has been made to set forth the best embodiment thereof, it should be understood that changes may be made within the scope of the following claims without departing from the spirit of the invention.

I claim:

1. A hydraulic torque relief mechanism including:
a hollow gear housing,
a motor secured to said housing and including a drive shaft extending into the interior thereof,
an externally vaned rotor secured to said drive shaft,
an internally vaned stator enclosing said rotor and including a plurality of angularly spaced apertures adjoining said rotor,
a driven shaft extending from said housing,
gear reduction means connecting said stator to said driven shaft,
said gear housing including lubricating fluid to a level above the level of said stator,
whereby rotation of said rotor by said motor will transfer rotary force through said fluid to said stator and through said gear reduction means to said driven shaft.

2. A hydraulic torque relief mechanism including:
a hollow gear housing,
a drive shaft extending into said housing,
a driven shaft extending from said housing,
a hydraulic clutch connected between said drive shaft and said driven shaft,
said clutch including an externally vaned rotor and a stator,
said stator including a pair of discs on opposite sides of said rotor and a peripheral wall connecting said discs and including inwardly extending stator vanes extending into close proximity with said rotor,
at least one of said discs including a plurality of angularly spaced apertures adjoining the vanes of said rotor,
said housing being filled with hydraulic fluid to a level about said hydraulic clutch,
whereby rotation of said drive shaft will act through the fluid in said stator to drive said driven shaft.

3. The structure of claim 2 and including a gear reduction train between said hydraulic clutch and said driven shaft.

4. A rotatable sign including:
a gear housing including a hollow body,
a drive shaft extending into said body,
a vertical driven shaft extending from said body,
a sign body including a vertical shaft connected to said driven shaft and with which said sign body rotates,
a hydraulic clutch connected between said drive shaft and said driven shaft in said gear housing,
said clutch including an externally vaned rotor connected to one of said drive and driven shafts,
a stator housing including an internally vaned housing enclosing said rotor and connected to the other of said drive and driven shafts,

said stator housing having apertures therethrough outwardly of said rotor, and
said gear housing including hydraulic fluid to a level above said clutch.

5. The structure of claim 4 and including a gear reduction train connecting said stator housing to said driven shaft.

6. The structure of claim 4 and in which said stator includes a pair of spaced discs and an internally vaned peripheral rotor encircling ring connecting said discs, said apertures extending through at least one said disc,

7. The structure of claim 6 and in which said apertures extend through both said discs.

8. The structure of claim 4 and in which said apertures

are in angularly spaced relation about the axis of said rotor and are spaced apart a distance greater than the angular distance between said vanes of said rotor.
